US00D754390S

(12) **United States Design Patent**
Mittersinker et al.

(10) **Patent No.:** **US D754,390 S**
(45) **Date of Patent:** **** Apr. 19, 2016**

(54) **SMOKING ACCESSORY**

(71) Applicant: **Philip Morris Products S.A.**, Neuchatel (CH)

(72) Inventors: **Gregor Mittersinker**, Warwick, RI (US); **Aaron Abroff**, Acton, MA (US); **Laurent Manca**, Grandvaux (CH)

(73) Assignee: **PHILIP MORRIS PRODUCTS S.A.**, Neuchatel (CH)

(**) Term: **14 Years**

(21) Appl. No.: **29/498,177**

(22) Filed: **Jul. 31, 2014**

Related U.S. Application Data

(62) Division of application No. 29/422,430, filed on May 21, 2012, now Pat. No. Des. 736,994.

CLAIM

The ornamental design for a smoking accessory, as shown and described.

DESCRIPTION

FIG. 1 shows a perspective view of the back, top, and left side of the design for a smoking accessory; FIG. 2 shows a right side view thereof; FIG. 3 shows a top plan view thereof; FIG. 4 shows a left side view thereof; FIG. 5 shows a bottom plan view thereof; FIG. 6 shows a front plan view thereof; FIG. 7 shows a back plan view thereof; FIG. 8 shows a perspective view of the back, top, and left side of another embodiment of the design for a smoking accessory;

FIG. 9 shows a right side view thereof;

FIG. 10 shows a top plan view thereof;

FIG. 11 shows a left side view thereof;

FIG. 12 shows a bottom plan view thereof;

FIG. 13 shows a front plan view thereof; and,

FIG. 14 shows a back plan view thereof.
